UNITED STATES PATENT OFFICE.

WILFRID HEUSSER, OF SALT LAKE CITY, UTAH.

MULTIPLE-WEIGHT ATTACHMENT FOR PRECISION-BALANCES.

1,345,180.

Specification of Letters Patent. Patented June 29, 1920.

Application filed April 4, 1918. Serial No. 226,766.

To all whom it may concern:

Be it known that I, WILFRID HEUSSER, a citizen of Switzerland, and a resident of Salt Lake City, in the county of Salt Lake 5 and State of Utah, have invented certain new and useful Improvements in Multiple-Weight Attachments for Precision-Balances, of which the following, together with the accompanying drawings, constitutes a full, 10 clear, and exact specification, which will enable others skilled in the art to which my invention appertains to make and use the same.

My invention relates to improvements in 15 multiple weight attachments for assay or analytical balances and its principal object is to provide improved facilities for easily and quickly applying very small weights to, or withdrawing the same from 20 the balance, without unduly disturbing its equilibrium.

The features upon which protection is desired are collectively grouped in the appended claims.

25 In the drawings:—

Figure 1 represents a portion of an ordinary assay balance embodying my improvement.

Fig. 2, a transverse vertical section thereof and Figs. 3, 4, 5, 6 and 7, fragmentary views showing various details.

Fig. 8 represents a section taken on line 8—8 in Fig. 9, illustrating a modified construction of my device, and

35 Fig. 9 is a transverse vertical section thereof.

Throughout the different views similar parts are designated by similar numerals.

Referring to the drawings (11) represents 40 a portion of the base, and (12) a portion of the beam, of an ordinary balance. The pan hanger (13) is suspended from one end of the beam in the usual manner, but the hanger is somewhat longer than is generally used, so as to provide the necessary space 45 between the pan (14) and the top of the hanger for accommodating the perforated plate or grid (15) and the extremities of the arms 16, 17, 18, etc.

50 These arms have their rear ends fulcrumed on the shaft 26, the latter being supported by the standards 25, which are rigidly mounted on the balance-base 11 in any suitable manner. The arms 16, 17, 18, 55 etc., are spaced apart from each other and from the standards 25 by the fiber friction

washers 27 strung on the shaft 26. Those washers 27, which are located between any pair of the arms 16, 17, 18, etc., have interposed the short arms 28 which are also 60 strung on the shaft 26. A pin 29 passes through the standards 25 and through the depending arms 28, thus preventing the latter from having any movement around the shaft 26, so that no motion can be communicated from one arm to its neighbor. The arms 16, 17, 18, etc., together with the interposed washers 27 and arms 28 are snugly wedged in between the standards 25, so as to 65 hold the arms in position under yielding 70 pressure.

Near their forward ends the arms 16, 17, 18, etc., carry respectively the conically tipped staffs 16^a, 17^a, 18^a, etc., these being so arranged that when the arms are moved up 75 and down the conical tips will pass centrally, or nearly so, through the corresponding holes in the grid 15.

Near their fulcrum, the arms 16, 17, 18, etc., have pivoted, downwardly extending 80 connecting rods 30, which also pivotally engage the arms 32^a of a series of bell cranks, 32, having a common fulcrum on the shaft 33, the latter being supported by the depending-standards 35, rigidly attached to 85 the base 11. The bell cranks 32 are spaced apart from each other and from the standards 35 by fiber friction washers 36 strung on the shaft 33. Those washers 33, which are located between any pair of the bell 90 cranks 32, have interposed the short arms 37, which are also strung on the shaft 33. The pin 38 passes through the upper extremities of arms 37.

The arms 32^b of the bell cranks 32, have 95 pivoted thereto, the rear ends of adjustable connecting rods 39, the forward ends thereof being pivoted to the depending arms 16^b, 17^b, 18^b, etc., which form parts of the depressible keys 16^c, 17^c, 18^c, etc., these being 100 fulcrumed on the shaft 40.

The shaft 40 is supported in the bracket 41, which is preferably made of cast metal and may be fastened to the underside of the base 11 by screws 42 (Figs. 1 and 2). 105 The bracket 41 (Figs. 1, 2, 4 and 6) has the slots 16^d, 17^d, 18^d, etc., formed therein to accommodate the corresponding keys 16^c, 17^c, 18^c, etc., and furthermore has also formed therein the slots 43, these being intermediate the first named slots, thus providing the leaves 44, Figs. 4 and 6. On 110

either side of each key 16^e, 17^e, 18^e, etc., (Fig. 4), is a fiber friction washer 45, both of which, together with the interposed key, are tightly fitted into position between two 5 of the leaves 44, the latter thereby exerting a yielding pressure on the friction washers 45 and therefore also against the keys 16^e, 17^e, 18^e, etc.

The arms 32^b, and the arms 16^b, 17^b, 18^b, etc., have V-shaped jaws at their lower extremities, as shown in Figs. 2 and 7, in order to receive the ends of the rods 39 and these are connected thereto by the pins 31. Fig. 7 shows an enlarged detail of one of the 15 V-shaped jaws and the pin 31 engaged by an end of one of the rods 39.

The balance-base 11 is supported on the usual leveling screws (not shown), which provides sufficient space for the operating 20 parts under the base.

The upward travel of the keys 16^e, 17^e, 18^e, etc., may be limited by coming in contact with the underside of the base 11, (Figs. 1 and 2), and the downward travel of the 25 keys may be limited by the bracket 41.

In use, the weights 16^e, 17^e, 18^e, etc., which are preferably in the form of circular washers of varying thicknesses, are poised on the conical tips of the staffs, in 30 the order corresponding to any denominations to which the keys 16^e, 17^e, 18^e, etc., may be indexed, the latter in their normal positions being pushed up close against the underside of the base 11.

35 Normally, the weights are held high enough above the grid 15 to be clear of the same at the uppermost point of the vibration of the balance.

When it is desired to use a certain weight, 40 the operator depresses the corresponding key, the depressed position being indicated by dotted lines in Fig. 2, this action depositing the weight on the grid 15, while the staff is carried down to its lowermost position, where the conical tip will be entirely clear of the grid.

When it is desired to remove a weight from the grid, the operator elevates the corresponding key, this action causing the staff 50 to lift the weight off the grid and to carry it back to the normal position, the key and the parts controlled by it, being prevented from dropping back, by the various friction washers under yielding pressure, as described.

Any necessary adjustments to fix the extreme travel of the weight-carrying staffs may be effected by the sleeves 46, which engage the rods 39.

60 Those parts of my device which are located above the base 11 are inclosed by the usual glass case 52, (Fig. 2) common to all balances and at 52 is a felt dust guard through which the rods 30 have their movement.

Figs. 8 and 9 illustrate a simplified construction of this invention, in which the arms 16, 17, 18, etc., are operated from above instead of being operated from below.

The rods 16^f, 17^f, 18^f, etc., at their lower 70 extremities, are pivoted to the arms 16, 17, 18, etc., and extend through guide holes in the top 47 of the balance-case, each rod being surrounded by the felt dust guard 49. At 48 are adjustable finger pieces, forming 75 at the same time, stops for limiting the downward travel of the rods 16^f, 17^f, 18^f, etc., the upward travel of these rods being limited by the adjustable collars 50.

The friction washers 27, short arms 28, standards 25, etc., have already been described. The standards 25 have set screws 51, which may be tightened upon the shaft 26, allowing the standards to be sprung together and secured under pressure, against 80 the washers 27, thus producing sufficient friction to hold the arms 16, 17, 18, etc., in any position.

Having fully described my invention, what I claim is:

1. In a multiple weight attachment for balances, the combination with the balance structure, of a suitably disposed grid having perforated depressions therein, washer-like weights adapted to rest in the said depressions, a plurality of suitably formed staffs adapted to move up and down through the perforations in the said grid, arms for supporting the said staffs, a plurality of operating keys suitably fulcrumed, means for 95 frictionally holding the said keys under yielding pressure and means for communicating motion from the said keys to the said arms.

2. In a multiple weight attachment, the 105 combination with a balance having a base and an oscillating beam with a pan hanger suspended therefrom, of a perforated grid attached to the said pan hanger, washer-like weights adapted to rest in the perforations of the said grid; conically tipped staffs adapted to engage the said washer-like weights, fulcrumed levers adapted to allow mounting of the said staffs near the free ends thereof, the said levers being positioned to permit the tips of the said staffs to be moved up and down through the corresponding perforations in the said grid; a standard rigidly mounted on the said base and adapted to carry the fulcrum of the 110 said levers, suitably disposed bell cranks with pivoted connecting rods extending from the said levers to arms of the said bell cranks; indexed depressible keys suitably pivoted, with arms extending therefrom, and adjustable connecting rods extending from the other arms of the said bell cranks to the arms of the said depressible keys, all as specified.

3. In a multiple weight attachment for 115 120 125 130

- balances, the combination with the balance structure, of a horizontally disposed grid having countersunk holes therein, the walls of the holes sloping inwardly from top to bottom; washer-like weights adapted to rest on the said sloping walls and to be centered thereby with the vertical axes of the said holes; staffs with conical tips adapted to engage the said weights; pivoted arms for supporting the said staffs; suitably disposed bell cranks with connecting rods extending to the said arms; and a series of depressible operating keys with adjustable connecting rods extending therefrom to the said bell cranks, the entire combination being so arranged that any of the said washer-like weights may be deposited on, or lifted from, the said grid, by moving the corresponding operating keys.
4. In a multiple weight attachment for balances having a suitable pan hanger, a grid having openings for receiving weights, staffs adapted to move up and down through the said opening, fulcrumed arms on which the staffs are mounted, the combination therewith, of means for frictionally holding the said arms under yielding pressure, and means for preventing the communication of motion from one of the said arms to an adjacent arm.
5. In a multiple weight attachment for balances having a grid, pivoted arms arranged adjacent to each other and carrying staffs adapted to move up and down through openings in the said grid, and depressible keys for operating the said arms, the combination therewith, of means for frictionally holding the said arms in any desired position, and means for preventing any one of the said arms from communicating motion to an adjacent arm when the key corresponding to the first-mentioned arm is operated.
6. In a device of the kind described, the combination with a balance having a base and an oscillating beam with a pan-hanger suspended therefrom, of a perforated grid attached to the said hanger, washer-like weights adapted to rest over the perforations of the said grid, conically tipped staffs adapted to engage the said washer-like weights, fulcrumed levers adapted at their free ends to carry the said staffs, the said levers being positioned to permit the tips of the said staffs to be moved up and down through the corresponding perforations in the said grid, a support adapted to carry the fulcrums of the said levers, suitably disposed bell cranks with pivoted connecting rods extending from the said levers to arms of the said bell cranks, indexed depressible keys suitably pivoted, with arms extending therefrom and adjustable connecting rods extending from the other arms of the said bell cranks to the arms of the said depressible keys, all as specified.
7. In a multiple weight attachment for balances, having a grid carried by a pan-hanger, pivoted arms arranged adjacent to each other and carrying staffs adapted to move up and down through openings in the said grid and depressible keys for operating the said arms, the combination therewith, of means for holding the said arms in any desired position under yielding pressure, and means for preventing any one of the said arms from communicating motion to an adjacent arm.
8. In a multiple weight attachment for balances having a grid carried by a pan-hanger, pivoted arms arranged adjacent to each other and carrying staffs adapted to move up and down through openings in the said grid and depressible keys for operating the said arms, the combination therewith, of means for preventing any one of the said arms from communicating motion to an adjacent arm when the depressible key corresponding to the first-mentioned arm is operated.
- In testimony that I claim this invention as my own, I affix my signature in the presence of two subscribing witnesses.
